ADJUSTABLE LATCH OR CLOSURE DEVICE

George L. Eber and Jacob Eber, Bronx, N. Y.

Application February 11, 1931. Serial No. 514,928

8 Claims. (Cl. 292—45)

This invention relates to closure devices adapted for use in connection with relatively movable body members such for example as the telescoping members or parts of a suitcase, trunk, box or the like; and the object of the invention is to provide a latch or closure device involving an adjustable element or elements whereby the separate parts or members may be secured in different positions of adjustment and secured against movement in one direction with respect to each other; a further object being to provide means for quickly releasing the securing or latching means of the separate devices to facilitate the quick separation or detachment of the respective parts or members; a further object being to provide a device of the class described including means for locking the same in different positions of adjustment and still further to the provision of means for movably supporting one of the parts or members with respect to the device independent of the movement of the device itself; a further object being to provide a single means for actuating two latch or securing units of the class described constituting part of one complete box or other container; and with these and other objects in view, the invention consists in a device and article of manufacture of the class specified, which is simple in construction, efficient in use, and which is constructed as hereinafter described and claimed.

The invention is fully disclosed in the following specification, of which the accompanying drawings form a part, in which the separate parts of our improvement are designated by suitable reference characters in each of the views, and in which:

Fig. 1 is a diagrammatic, sectional plan view through a container indicating one method of arranging our improved securing devices in connection therewith, the section being on the line 1—1 of Fig. 2.

Fig. 2 is a section on the line 2—2 of Fig. 1, on an enlarged scale.

Fig. 3 is a section on the line 3—3 of Fig. 1, on an enlarged scale.

Fig. 4 is a perspective view of the container shown in Figs. 1 to 3 inclusive in closed position.

Fig. 5 is a partial section on the line 5—5 of Fig. 2 on an enlarged scale.

Fig. 6 is a view similar to Fig. 5 showing only a part of the construction and with parts in a different position.

Fig. 7 is a partial section on the line 7—7 of Fig. 5.

Fig. 8 is a partial section on the line 8—8 of Fig. 7, parts of the construction being shown in full lines.

Fig. 9 is a partial section on the line 9—9 of Fig. 8; and,

Fig. 10 is a partial section on the line 10—10 of Fig. 8.

While our invention is adaptable for many uses, for the purpose of illustrating one method of carrying the invention into effect, we have shown in the accompanying drawings the same applied to such articles of manufacture known as telescoping, collapsible and extensible boxes, bags, suitcases, trunks and the like.

In the drawings, 11 represents one part or member of such article, and 12 the other part telescoping or otherwise collapsible with respect to the part 11. Both of said parts may be constructed of any suitable material including the usual facings, linings, reinforcements and the like commonly employed in the production of articles of the class hereinbefore mentioned, all of which structural details have been eliminated in order to simplify the showing of the invention. For the purpose of description, the part 11 will be regarded as the main container and the part 12 as a cover therefor.

Opposed walls 11a and 11b of the part 11 are provided, adjacent the ends thereof, with vertically arranged apertures 13. Movable disposed in the apertures 13 of the wall 11a are blocks 14, the outer ends which move through the apertures and project externally of said walls being relatively small and terminate in upwardly directed hinge lugs 15, to which are pivotally coupled hasps 16 cooperating with key-controlled locks 17 on the outer faces of a corresponding side wall 12a of the part 12.

Other blocks 18 are slidably mounted in the apertures 13 of the wall 11b, and these blocks differ from the blocks 14 simply by pivoting mounting plates 19 in connection with the outer ends of the blocks 18 forming a hinge structure for hingedly supporting the cover part 12 in connection with the part 11, it being understood that the plates 19 are secured to the side wall 12b of the cover. Aside from this structural difference, the blocks 14 and 18 are of identical construction, and the brief description of one will apply to the other. Each of these blocks constitutes a part of a latch or securing device.

In Figs. 5 to 8 inclusive, one of the latch devices is shown in detail. These devices consist, in the construction shown, of two rods 20 and 21 arranged in spaced parallel relation with respect to each other and upon which the enlarged inner ends of the blocks 14 and 18 are mounted for sliding movement longitudinally with respect thereto, the rods passing through apertures in said blocks. The upper and lower ends of said rods are coupled together and spaced apart by coupling strips 22 and 23 in which the rod 20 is rotatably mounted, said rod having longitudinally

of one side face thereof, projecting ratchet teeth 20a adapted to be moved into and out of engagement with a spring actuated pawl 24 pivotally supported on the top of the enlarged inner end of the blocks 14-18 between the rods 20 and 21. A spring 25 is mounted on the rod 21 and serves to move the block slidably engaging said rod in an upward direction on the rod.

At the lower end of the rod 20 of each latch unit is secured a crank arm 26. The crank arm 26 of one unit employing the block 14 is coupled with the opposed unit having the block 18 by links 27-27a so that the rotation of the rod 20 in the blocks 14 will correspondingly rotate the rods 20 in the blocks 18 in moving the ratchet teeth 20a into and out of engagement with the pawl 24 or from the position shown in Fig. 5 to that shown in Fig. 6 or vice versa, in controlling the movement of the member 12 upwardly with respect to the member 11.

It will also be noted that the crank arms 26 of the units arranged on the wall 11a are coupled together by an operating rod 28, the operation of which is controlled by a knob 29 projecting through the wall 11a and having on the inner face of said wall a crank 30, the free end of which is provided with an elongated slot in which a pin 31 on the rod 28 operates. By rotating the knob 29 in different directions, the rod 28 may be moved to the left or right with respect to the wall 11a as will be apparent, and impart in this operation, the two rotary oscillatory movements to be contributed to the rods 20 to move them into the position shown in Figs. 5 and 6 or to move the ratchet teeth 20a of said rods into and out of engagement with the pawls 24.

At this time, it will be understood that if the part 12 be locked or latched in predetermined position with respect to the part 11 by virtue of the fact that the pawls 24 are in engagement with the ratchets 20a on the rods 20 of all the latch units, and it is desired to open the box or case, by simply turning the knob 29 in a clockwise direction, the ratchet teeth will be disengaged from the pawls and the springs 25 will operate to automatically move the cover 12 upwardly. By opening the locks 17 securing the hasps 16 in position by means of a suitable key, the cover 12 may be swung into open position in the manner indicated in dotted lines in Fig. 2 of the drawings, it being understood that this cover may assume any desired position with respect to the container part 11. The pivotal movement of the cover is performed when the same is in the raised position, it being understood that in employing a comparatively deep cover, the same cannot be swung into open position if the blocks 14-18 are locked at too low a point on the container part 11. It will also be understood at this time, that to reset the cover in any desired position upon the container 11, the knob 29 will be turned in an anti-clockwise direction to return the ratchet teeth 20a into engagement with the pawls 24. When the cover is locked or secured in position with the hasps or other means employed, by simply forcing the cover downwardly, the blocks 14 and 18 will be moved downwardly on the rods and automatically locked into any position of adjustment by the engagement of the pawls with the ratchet teeth.

In the accompanying drawings, the bar 28 is shown in spaced relation to the adjacent wall 11a of the container and this is simply for clearness of showing, it being understood that this bar will

be so fashioned as to be arranged in close proximity to the inner surface of said wall.

We also preferably enclose the links 27-27a as well as the rods 20-21, blocks 14 and 18 and members 22 and 23 in channel-shaped casings 32 and 32a, each casing extending from one unit on the front wall 11a across the bottom wall of the container 11 and onto the opposed wall 11b. This will protect the clothes or other articles placed in the container 11 from coming in contact with the mechanism of the latch or securing devices which are employed. If desired, the protruding rod 20 and its controlling means may be arranged in a similar enclosure or built into the wall structure of the container 11.

We also preferably employ in conjunction with each of the apertures 13, shutter plates 33 and 34 loosely coupled together as seen at 35, the plate 33 being attached to the lower surface of the blocks 14-18 whereas the plate 34 includes a flange 36 preventing displacement from the adjacent wall of the container. These plates serve to close the apertures 13, presenting a neat and finished external appearance, and also preventing dust and dirt from collecting in the case to interfere with the operation of the latch and securing devices.

We also preferably employ inwardly of the plates 33 and 34, a liner plate 37 having apertures through which the blocks 14-18 pass, and this liner plate also serves to protect and guard the mechanisms of the separate devices. It will be understood that the shutter plate 33 is movable longitudinally of the plate 34 when the blocks 14-18 are moved downwardly in the apertures 13, and the interengagement of said plates at 35 causes the plate 33 to lift the plate 34 in the upward movement of the blocks 14-18.

By providing two pairs of latching units disposed on front and back walls of telescoping case or container parts in the manner illustrated in Figs. 1 to 4 inclusive, it will be apparent that a very strong and easily and properly functioning latching means is provided, whereby articles placed within the container and the cover of the container may be securely packed and held in position by simply forcing the cover 12 downwardly over the container 11, the pawls of each device engaging the ratchet teeth 20a of each rod 20 in this operation. It will be understood that the springs 25 are placed under compression, so that in the operation of opening the case or container, when the rods 20 are moved to disengage the ratchet teeth from the pawls, said springs will automatically function to raise the cover, permitting the movement thereof into open position when the hasp lock or other locking means is released.

It will be understood that our invention is not necessarily limited to the use of the two rods 20-21 in each unit, nor are we limited to any specific type of locking or securing means employed between the movable blocks 14-18 and the cover 12, nor in fact, to the use of the hinge connection of the cover with the blocks 18. Still further, our invention is not necessarily limited to the specific means herein disclosed for controlling the operation of the rods 20, and various other changes in and modifications of the construction herein shown and described may be made within the scope of the appended claims without departing from the spirit of our invention or sacrificing its advantages.

Having fully described our invention, what we

claim as new and desire to secure by Letters Patent, is:

1. A device of the class described comprising a casing, a guide rod in said casing, a block slidably engaging said rod within the casing and having a part projecting through the casing, means spaced longitudinally of said rod adapted to be engaged by a member on said block for retaining the block against movement in one direction with respect to said rod, said rod being adjustable to move the means thereon out of engagement with said member to permit free movement of the block on the rod in both directions, and means in the casing independent of said rod and cooperating with said block for retaining the same against rotation in the casing. 80
2. A device of the class described comprising a casing, a guide rod in said casing, a block slidably engaging said rod within the casing and having a part projecting through the casing, means spaced longitudinally of said rod adapted to be engaged by a member on said block for retaining the block against movement in one direction with respect to said rod, said rod being adjustable to move the means thereon out of engagement with said member to permit free movement of the block on the rod in both directions, and means in the casing independent of said rod and cooperating with said block for retaining the same against rotation in the casing, said last named means involving a rod arranged in parallel relation to the first named rod and on which said block is slidably mounted. 85
3. A device of the class described comprising a casing, a guide rod in said casing, a block slidably engaging said rod within the casing and having a part projecting through the casing, means spaced longitudinally of said rod adapted to be engaged by a member on said block for retaining the block against movement in one direction with respect to said rod, said rod being adjustable to move the means thereon out of engagement with said member to permit free movement of the block on the rod in both directions, and means in the casing independent of said rod and cooperating with said block for retaining the same against rotation in the casing, said last named means involving a rod arranged in parallel relation to the first named rod and on which said block is slidably mounted. 90
4. In a container having telescoping parts, a latch device for retaining the container parts in different telescoped positions and permitting movement of said parts toward and from each other, said device comprising a casing mounted in connection with one wall of one of said container parts adjacent an elongated aperture therein, a block slidably mounted in the casing and including a member projecting therethrough and through the aperture in said container part, means in said casing for guiding the block in its movement therein, said means involving a guide rod having longitudinally spaced teeth, a pawl on said block adapted to engage the teeth in said rod in one position of said rod to retain the container parts against separation, and means for rotating said rod to move said teeth out of engagement with said pawl to permit free movement of the container parts with respect to each other. 95
5. In a container having telescoping parts, a latch device for retaining the container parts in different telescoped positions and permitting movement of said parts toward and from each other, said device comprising a casing mounted in connection with one wall of one of said container parts adjacent an elongated aperture therein, a block slidably mounted in the casing and including a member projecting therethrough and through the aperture in said container part, means in said casing for guiding the block in its movement therein, said means involving a guide rod having longitudinally spaced teeth, a pawl on said block adapted to engage the teeth in said rod in one position of said rod to retain the container parts against separation, and means for rotating said rod to move said teeth out of engagement with said pawl to permit free movement of the container parts with respect to each other, and the member of said block and the other container part having interengaging coupling elements for retaining said container parts against displacement. 100
6. The combination with a container, opposed walls of which are provided with vertically arranged elongated apertures and a cover member having a telescoping engagement with respect to said container, of latching devices involving members movable vertically in said apertures and having parts projecting outwardly through the container and to which said cover is adapted to be attached, and means involving a pawl and rack within the container adjacent the apertures in the walls thereof and cooperating with said members for retaining the same and said cover against movement in one direction with respect to the container. 105
7. The combination with a container, opposed walls of which are provided with vertically arranged elongated apertures and a cover member having a telescoping engagement with respect to said container, of latching devices involving members movable vertically in said apertures and having parts projecting outwardly through the container and to which said cover is adapted to be attached, means involving a pawl and rack within the container adjacent the apertures in the walls thereof and cooperating with said members for retaining the same and said cover against movement in one direction with respect to the container, and means for moving said pawl and rack into inoperative position permitting free movement of said members and the cover with respect to the container. 110
8. The combination with a container, opposed walls of which are provided with vertically arranged elongated apertures and a cover member having a telescoping engagement with respect to said container, of latching devices involving members movable vertically in said apertures and having parts projecting outwardly through the container and to which said cover is adapted to be attached, means within the container adjacent the apertures in the walls thereof and cooperating with said members for retaining the same and said cover against movement in one direction with respect to the container, means for moving said last named means into inoperative position permitting free movement of said members and the cover with respect to the container, and said last named means involving a single, manually operated control simultaneously releasing all of said members. 115
